Primary Examiner — Wan Laymon*(74) Attorney, Agent, or Firm* — McMillan LLP**CLAIM**

An ornamental design for an orthodontic appliance, as shown and described.

DESCRIPTION

FIG. 1 is a lower front perspective view of the orthodontic appliance shown as used in its environment;

FIG. 2 is a top perspective view of the design of FIG. 1;

FIG. 3 is a front view of the design of FIG. 1;

FIG. 4 is a right side view of the design of FIG. 1;

FIG. 5 is a top view of the design of FIG. 1;

FIG. 6 is a rear view of the design of FIG. 1;

FIG. 7 is a left side view of the design of FIG. 1; and,

FIG. 8 is a bottom view of the design of FIG. 1.

The broken lines shown in the figures represent portions of the orthodontic appliance that form no part of the claimed design.
